UNITED STATES PATENT OFFICE.

FRANCES MARION SHEPHERD, OF MINNEAPOLIS, MINNESOTA.

DESIGN FOR A BRACKET.

SPECIFICATION forming part of Design No. 27,175, dated June 8, 1897.

Application filed April 12, 1897. Serial No. 631,862. Term of patent 7 years.

To all whom it may concern:

Be it known that I, FRANCES MARION SHEPHERD, a citizen of the United States, residing at Minneapolis, in the county of Hennepin 5 and State of Minnesota, have invented and produced a certain new and original Design for Brackets; and I do declare the following to be a full, clear, and exact description of the invention, such as will enable others skilled 10 in the art to which it appertains to make and use the same.

My invention has relation to a design for a window-bracket. It relates to the entire configuration of the bracket.

15 My invention relates particularly to the design for a window-bracket, as illustrated in the accompanying drawing, in which the figure is a perspective view of a bracket embodying my design.

20 The leading features of my design appear in the following description.

1 represents a rectangular clamp, consisting of the standard 2 and the horizontal par-

allel arms 3 4, the inner face of the former being provided with transverse parallel V- 25 shaped ribs 5 5.

8 represents a horizontal arm extending outwardly from the standard 2 and having a plane face 9 converging from the standard to its semicircular end 12. 30

13 represents a central curved web or rib connecting the lower face of the arm 8 with the outer face of the standard.

14 14 represent vertical screw-orifices extending through the horizontal arm 8. 35

Having thus fully described my invention, what I claim as new, and desire to secure by Letters Patent of the United States, is—

The design for a window-bracket, substantially as herein shown and described. 40

In testimony whereof I hereunto affix my signature in presence of two witnesses.

FRANCES MARION SHEPHERD.

Witnesses:

ORTON S. CLARK,
S. G. POSTON.
